LIQUEFIED GAS ODORIZER AND METHOD
OF USING SAMEWalter C. Dayhuff, Whittier, Calif., assignor to
Standard Oil Company of California, San
Francisco, Calif., a corporation of Delaware

Application August 8, 1938, Serial No. 223,708

7 Claims.

(Cl. 62—1)

This invention relates to the odorization of liquefied fuel gas, such as butane, propane and the like, and particularly refers to a method and means for releasing gas from the conventional container or portable cylindrical tank in which the liquefied gas is maintained under suitable pressure in such a manner that the concentration of odorant in the gas discharged from the container will remain substantially constant during the entire emptying procedure.

Odorization of liquefied gas fuel is considered necessary to provide protection against fire hazards and explosions which may result from gas leaks. The usual method of effecting odorization is to add the required amount of liquid odorizing material, for example, that described in United States Patent No. 2,094,270 issued September 28, 1937 to W. H. Hampton et al., directly to the liquefied gas stock. When this stock is converted into vapor by so-called cross-cut vaporization of the liquid, as by withdrawing liquid per se from its tank or container and then evaporating it in a preheater or vaporizer, the concentration of odorant in the liquid remains constant, and is identical with the concentration in the vapor. On the other hand, when vapor is withdrawn from the vapor space of a supply tank, as by reducing the pressure thereon, a weathering process or differential vaporization is involved, in which the odorant concentration of the gas is a function of the relative volatilities of odorant and liquefied gas, as well as odorant concentration in the liquid.

Odorants widely used at the present time are usually less volatile than the liquefied gases to which they are added, and as a result the first gas removed in differential vaporization carries less odorant with it than does the gas removed as the liquefied fuel charge in the cylinder approaches depletion. Furthermore, if the temperature of the tank or cylinder containing the liquefied gas becomes lower, as by cooling from evaporation or from other causes, the tendency for the odorant to remain in the tank becomes more marked as the liquefied gas evaporates and is withdrawn, resulting in large variations in the odor intensity of the withdrawn gas.

Attempts have been made to overcome this tendency by modifying the nature of the odorant or by adding retaining liquids, as in United States Patent No. 1,944,175 issued January 23, 1934. This invention, however, is entirely concerned with the method and means associated with removal of gas from the cylinder or container for

the liquefied gas and so is independent of such prior art practice.

This invention comprehends broadly a method and means for withdrawing gas from a cylinder or tank of odorized liquefied fuel gas including the step of passing said vaporized gas over an extended solid surface which is continuously wet with the liquefied material and then releasing the gas for any desired use.

10 It is an object of this invention to provide a method and apparatus for withdrawing odorized gas from a tank or cylinder containing a quantity of odorized liquefied gas with a smaller variation in odorant intensity in the gas than has heretofore been possible.

Another object is to provide a simple means that will function automatically and without attention to produce the desired result, and which may be installed in each cylinder or tank of liquefied fuel gas with slight expense and modification of the existing structure.

Another object is to provide a method of odorizing liquefied gas that will give a more uniformly odorized product, thereby permitting a smaller quantity of relatively expensive odorant to be used to produce a given odorant intensity in the gas.

Another object is to provide an odorizer that will function even when the tank or cylinder is not actually connected to a gas distributing system, to indicate a leak in the tank or in the shut-off valve thereon.

These and other objects and advantages will be apparent from the following description and from the accompanying drawing, which forms a part of this specification and illustrates a preferred embodiment of the invention as applied to a conventional cylinder of liquefied fuel gas.

In the drawing, Figure 1 is a vertical and part sectional view of a liquefied gas cylinder with its discharge connection modified to practice this invention.

Figure 2 is a longitudinal sectional view, to a somewhat larger scale, of a discharge connection and wick suitable to practice the invention.

The usual construction of a tank or cylinder for liquefied gas, such as propane, butane and the like, includes a tank shell 10, usually of drawn steel, to which is secured a cap or closure 11, threaded as at 12 to receive a similarly threaded valve member 13. Valve 13 is fitted at one side with a threaded outlet 14 and a suitable valve stem 15, by means of which the release of gas from the tank may be controlled.

In order to provide an extended solid wetted

surface over which the vapor or gas must pass in leaving tank 10, the inlet to valve 13 is threaded as at 16 to receive a nipple 17 and pipe 18, the latter extending substantially to the bottom of tank shell 10. Pipe 18 is perforated at intervals as at 19, and is preferably so arranged that all the gas or vapor leaving tank 10 must pass along a substantial portion of its length. Preferably the perforations 19 are closer together at the upper end of pipe 18, as shown.

The extended solid wetted surface may be of any suitable material, but in the example shown is a wick of soft cotton or other capillary material 20, extending throughout pipe 18 and preferably provided with some means for retaining it in place, such as pin 21. Liquefied fuel gas cylinders of this type are invariably placed in the upright position shown when they are connected for use, so that the wick 20 will always be wet for at least a portion of its length so long as any odorized liquefied gas remains in tank 10.

The explanation for the operation of this invention is not definitely understood, but its usefulness has been demonstrated by numerous successful tests, and appears to involve only the step of intimately contacting the outgoing gas or vapor with an extended solid surface wetted by the odorized liquid. Obviously other means than that shown could be utilized for carrying out this procedure. With variations in temperature between 32° F. and 90° F. and for full and half empty cylinders the variation in odor intensity of the withdrawn gas or vapor was found to be negligible. Also, the odor intensity of gas withdrawn from cylinders using this method was at least twice as great as that withdrawn from cylinders of the same material and containing the same kind and amount of odorant but where the outgoing gas was not contacted with the extended solid wetted surface.

Although but a single application of the method and a single specific example of means for practicing this invention are described above, it is obvious that numerous modifications and changes could be made without departing from their essential features, and all such that come within the scope of the appended claims are embraced thereby.

I claim:

1. In the method of odorizing liquefied fuel gas such as butane, propane and the like, to which a volatile odorant material has been added in the liquid phase, and which is maintained in liquid phase by being stored under pressure, the steps of releasing the pressure on said liquefied gas so that it will evaporate and contacting said

vapor with an extended solid surface wetted by said liquefied gas.

2. The method of odorizing a liquefied hydrocarbon or a mixture of hydrocarbons, such as butane, propane, and the like, comprising the steps of adding an odorant material to said liquefied hydrocarbon, maintaining said odorized hydrocarbon in a container under a pressure adequate to maintain a liquid phase and a vapor phase in said container, withdrawing only vapor phase hydrocarbon from said container by releasing the pressure thereon, and, prior to its withdrawal, contacting said vapor phase hydrocarbon with an extended solid surface in said container wetted with the liquid phase of said hydrocarbon.

3. In combination with a pressure container for odorized liquefied gas, only a single valved outlet means for releasing gas from said container and means in said container adapted to provide an extended surface wetted by the liquefied gas in said container and in communication with said outlet, so constructed and arranged that gas released from said container will first contact said extended surface.

4. A combination as defined in claim 3 in which said last named means extends substantially throughout the height of said container so as to be wetted by any liquefied gas which may remain in said container.

5. An attachment for an odorized liquefied gas container having a single outlet opening therefrom comprising a conduit adapted to be placed within said container and to be connected to the outlet of said container, means for permitting gas and liquid from said container to enter said conduit at any level of the liquid in said container, and means in said conduit forming an extended surface adapted to be wetted by the liquid in said container and to be contacted by the gas passing to the outlet of said container.

6. An odorizer for liquefied gas containers as defined in claim 5 in which last named means comprises a capillary material.

7. An attachment for an odorized liquefied gas container comprising a tube adapted to extend inwardly from the outlet of said container to a point near the bottom thereof, a plurality of openings in the wall of said tube, so that gas released from said liquid in said container may enter said tube regardless of the level of the liquid in said container and a wick of capillary material extending substantially throughout the length of said tube.
